UNITED STATES PATENT OFFICE.

ELIAS HENRY McCURDY, OF ROCHESTER, NEW YORK.

IRONING MACHINE.

Application filed May 28, 1926. Serial No. 112,313.

My present invention relates generally to laundry apparatus and more particularly to ironing machines, my primary object being the provision of a machine by means of which both ironing and pressing may be readily and quickly accomplished, as well as one capable of heating by gas, electricity, or steam and which may be easily controlled and manipulated.

10 A further object is the provision of a simple, inexpensive machine which will be strong and durable, capable of ready repair, and which will be effective and efficient in use.

15 With the above objects in mind certain further objects as well as the resulting advantages of my invention will be better understood from the following description in which reference is made to the accompanying drawings forming a part of this specification, and wherein:

Figure 1 is a perspective view illustrating the complete machine with the ironing and pressing member elevated.

20 Figure 2 is a top plan view thereof.

Figure 3 is a vertical transverse section taken substantially on line 3—3 of Figure 2, and,

Figure 4 is a partial vertical longitudinal section taken in line 4—4 of Figure 3.

Referring now to these figures, the ironing and pressing member generally indicated at 10 is connected at its opposite ends to the upper angular inturned ends 11 of a pair of arms 12, each of which arms has at its lower end a foot plate 13. The plates 13 ride the pins 14 projecting inwardly from the rear ends of a pair of levers 15 which are fulcrumed at 16 intermediate their ends upon bearing pieces 17.

The machine as a whole is seated upon a bed plate 18 from the sides 19 of which the bearing pieces 17 upstand, and upon the forward portions of which sides the offset portions 20 of a controlling foot bar 21 have bearing. At its opposite ends, this bar is in movable engagement with the forward ends of the levers 15, while its central portion, which forms a foot treadle 22, extends alongside the central reduced portion of the bed plate as shown especially in Figure 1 so that when pressed downwardly it forces the lever engaging ends 23 of the bar downwardly causing similar downward movement of the forward ends of the levers 15. This elevates the rear ends of the levers 15 and

consequently elevates the ironing and pressing member.

The central or treadle portion of the controlling bar is engageable by a laterally 60 swinging gravity latch 24 mounted on the central forward portion of the bed plate, which the operator may kick to one side or the other so as to permit the ironing and pressing member to descend.

65 The upper angular inturned ends 11 of the arms 12 before mentioned work on the upper reduced stems 25 of the upstanding side extensions 26 of a U-shaped frame 27 and these stems 25 which project through 70 openings in the ends 11 of the side arms 12, have thereon springs 28 which bear downwardly on the said ends 11 to force the ironing and pressing member downwardly when the latch 24 is released. The stems 25 moreover have nuts 29 which engage the upper 75 ends of the springs 28 and by means of which the tension of the springs may be adjusted.

75 The frame 27 is at its lower side portions 80 shiftable longitudinally guide brackets 30 and is provided at its central portion with rearwardly projecting spaced apart fingers 31 upon opposite sides of a cam disc 32 secured upon the shaft of a motor 33 so that 85 when the motor is in operation the frame 27 will be lengthwise reciprocated or vibrated and a similar movement will thus be imparted to the ironing and pressing member.

85 The ironing and pressing member moves 90 upwardly and downwardly under foot control by the operator, away from and toward the ironing board 34, the latter of which has spur rods 35 and 36 at its opposite ends for holding a cover thereon and the latter of which spur rods 36 is adjustable and under control of springs 37 so that a cover may be readily placed upon the board 34.

The board 34 is furthermore supported upon upright standards 38 and is provided upon 95 its under surface with a reinforcing beam 39, one end of which is pivotally connected at 40 to one of the standards 38 and the other end of which seats within the notched upper end of the other standard 38 so that the ironing board is thus prevented from lateral displacement, although it may be lifted at one end to permit the shifting of tubular articles around the ironing board and between the standards 38. The standards 38 are provided at their lower ends with hollow 100 rectangular slides 41 with which the stand-

ards are rigidly connected and these slides 41 are movably disposed upon similarly shaped guide brackets 42 disposed upon the side portions 19 of the bed plate so that the ironing board as a whole may be shifted forwardly and rearwardly with respect to the vertical plane of movement of the iron irrespective of whether the latter is moved upwardly or downwardly or lengthwise. 10 Thus, the operator by grasping the ironing board and sliding the same forwardly from beneath the iron, may conveniently change the cover of the ironing board or place the articles to be pressed or ironed thereon after 15 which it is a simple matter to shift the ironing board rearwardly beneath the iron for further operation.

Normally the parts are in the position shown in Fig. 1, that is, with the ironing and 20 pressing member elevated, the treadle 22 of the controlling bar 21 having been forced downwardly by the operator whereupon the gravity latch member 24 swings to vertical position in order that it may act as a lock to 25 hold the ironing member elevated. The ironing board 4 is then drawn forwardly and the articles to be pressed placed thereon, after 30 which it is again shifted rearwardly beneath the iron. Assuming that the articles are 35 simply to be pressed, the motor 33 is cut off and the operator with his foot upon the treadle 22 kicks the gravity latch member 24 to one side permitting the iron to descend flatwise upon the ironing board and of course upon the articles on the ironing board 40 without vibratory movement. Where it is desired to iron the articles, the motor 33 is started, and thus as the iron is lowered in the beforementioned manner on to the ironing board and on to the articles to be ironed, its vibratory or lengthwise reciprocating 45 movements will bring about the desired ironing operation, it being obvious that in either operation the operator remains in control of the pressure of the iron upon the goods, with his foot upon the treadle 22.

While it is obvious that irons of various form may be used having an enlarged body portion of approximately the dimensions of 50 the ironing board 34, and adaptable to the heating influence of steam, gas or electricity, I prefer an iron such as shown whose body indicated at 43, primarily intended for heating by gas, has a flexible gas supply connection 44 controlled by a valve 45 and which is provided upon its upper surface with ridges or ribs 46 through and between which the flame circulates over the upper surface of the iron within a cover 47 having side and top 55 openings 48 and 49 for the proper admission of air and to provide an outlet for the products of combustion. This cover preferably has an internal rib therearound adapted to seat upon the upper surface of the body 43 60 of the iron so that those portions of the cover

below its rib may telescope the sides of the iron body and form a snug connection providing against accidental displacement of the cover in use and at the same time for the ready removal of the cover for cleaning when 70 this becomes desirable or necessary.

It is obvious from the foregoing that my invention presents an apparatus capable of ready manipulation and control, which will be effective and efficient in use, which is 75 simple and comparatively inexpensive, and which is otherwise well adapted to the carrying out of the objects first above stated.

I claim:

1. An apparatus of the present character 80 including an ironing board, an iron disposed above the board and of substantially the proportions of the board, means for raising and lowering the iron with respect to the board including yieldable means for 85 urging the iron into engagement with the board, and means connected with the raising and lowering means for reciprocating the iron.

2. An ironing machine, comprising an 90 ironing board, an iron disposed above the board, vertically movable members carrying the iron, means for raising and lowering the said members, a horizontally slideable member, means for reciprocating said member 95 and means for connecting the said member with the vertically movable members.

3. An apparatus of the present character including an ironing member, an iron above 100 the board having depending supporting arms at its opposite ends, levers engaged at one end with the lower ends of said supporting arms, a treadle having connection with the opposite ends of said levers for raising and 105 lowering the same as well as the iron, and a gravity latch engageable with said treadle to hold the same in depressed position and lock the iron in elevated position with respect to the board.

4. In an ironing machine, a bed plate, an 110 ironing board, standards carrying the ironing board slidably mounted on the bed plate, an ironing and pressing member above the board, means for raising and lowering the ironing and pressing member, means for 115 reciprocating the ironing and pressing member having a sliding connection with the raising and lowering means, and a spring operably connected with said connection 120 for providing a yielding connection and forcing the ironing and pressing member downwardly when the raising and lowering means are released.

5. An apparatus of the character described, including a vertically movable and 125 lengthwise reciprocable iron, an ironing board normally positioned beneath the iron, standards supporting the ironing board and to one of which the board is hinged, and to the other of which the board is engaged 130

permitting its movement on the said hinge, said standards having slide members at their lower ends, and supporting brackets disposed horizontally beneath the board and on 5 which the slide members are movable permitting shifting of the board into and out of the vertical plane of the iron.

6. An apparatus of the present character including an ironing and pressing member, 10 upright arms having inturned upper ends secured to the ends of said member and having lower foot plates, levers pivoted below the arms and movably engaging said foot plates for raising and lowering the arms, and per- 15 mitting independent lateral movement of the latter, a treadle operatively connected to the opposite ends of said levers for actuating the latter, a reciprocable frame having ex- 20 tensions on which the said arms are shift- able vertically, springs on said extensions.

engaging the arms to force the latter and the ironing member downwardly, an ironing board beneath the ironing member, and connections for reciprocating said frame in the direction of its length whereby to impart 25 similar movement to the ironing member.

7. In an ironing machine, a bed plate, an iron having right angular arms extending from its ends, means mounted on the bed plate and connected with the vertical mem- 30 bers of the arms for raising and lowering the iron, a U-shaped frame mounted to slide on the bed plate and having its end members extending through openings in the horizontal members of the arms, springs on the 35 projecting ends of said members between nuts thereon and the said horizontal members, and means for reciprocating said U-shaped member.

ELIAS HENRY McCURDY.
